DESIGN FOR A GARMENT HANGER

Howard C. Riemann, West Milwaukee, Wis., assignor to The Fulton Company, West Allis, Wis., a corporation of Wisconsin

Application September 10, 1945, Serial No. 121,997

Term of patent 7 years

(CL. D80—8)

To all whom it may concern:

Be it known that I, Howard C. Riemann, a citizen of the United States of America, residing at West Milwaukee, in the county of Milwaukee and State of Wisconsin, have invented a new, original, and ornamental Design for a Garment Hanger, of which the following is a specification, reference being had to the accompanying drawing, forming a part thereof.

In the drawing:

Fig. 1 is a top plan view of a garment hanger showing my new design;

Fig. 2 is a rear perspective view of the garment hanger shown in Fig. 1; and

Fig. 3 is a front elevational view thereof.

I claim:

The ornamental design for a garment hanger, substantially as shown.

HOWARD C. RIEmann.
